(57) **CLAIM**

The ornamental design for a foldable baby bed, as shown and described.

DESCRIPTION

FIG. 1 is a perspective view of a foldable baby bed;

FIG. 2 is a rear elevational view thereof;

FIG. 3 is a front elevational view thereof;

FIG. 4 is a top elevational view thereof;

FIG. 5 is a bottom elevational view thereof;

FIG. 6 is a left side elevational view thereof; and,

FIG. 7 is a right side elevational view thereof.

The broken lines shown are included for the purpose of illustrating portions of the foldable baby bed that form no part of the claim.
